US00D830411S

(12) **United States Design Patent** (10) Patent No.: **US D830,411 S**
 Schindler (45) Date of Patent: ** Oct. 9, 2018

(54) **DISPLAY SCREEN WITH ICON**

(71) Applicants: **DMG MORI SEIKI CO., LTD.**, Yamatokoriyama-shi, Nara (JP); **DMG MORI SEIKI AKTIENGESELLSCHAFT**, Bielefeld (DE)

(72) Inventor: **Dominic Schindler**, Lauterach (AT)

(73) Assignees: **DMG MORI SEIKI CO., LTD.**, Nara (JP); **DMG MORI SEIKI AKTIENGESELLSCHAFT**, Bielefeld (DE)

(**) Term: **15 Years**

(21) Appl. No.: **29/580,588**

(22) Filed: **Oct. 11, 2016**
